UNITED STATES PATENT OFFICE.

HENRY DANIEL O'BRIEN, OF FORSYTH, MONTANA.

TRUSS.

1,244,766.

Specification of Letters Patent.

Patented Oct. 30, 1917.

Application filed June 28, 1917. Serial No. 177,539.

To all whom it may concern:

Be it known that I, HENRY DANIEL O'BRIEN, a citizen of the United States, residing at Forsyth, in the county of Rosebud and State of Montana, have invented a new and useful Truss, of which the following is a specification.

The device forming the subject matter of this application is a truss, and one object of 10 the invention is to provide a device of this kind which can be adjusted readily to accommodate body dimensions and to permit the pad portion of the truss to coöperate properly with the rupture.

Another object of the invention is to provide novel means for holding the pad on 15 the perineal strap.

It is within the province of the disclosure to improve generally and to enhance the 20 utility of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made within the 30 scope of what is claimed, without departing from the spirit of the invention.

In the accompanying drawings:—

Figure 1 shows in front elevation, a truss constructed in accordance with the invention, parts being broken away;

Fig. 2 is a perspective view showing the connected ends of the belt;

Fig. 3 is a section taken approximately on the line 3—3 of Fig. 1;

Fig. 4 is a section taken on the line 4—4 of Fig. 1;

Fig. 5 is a fragmental elevation showing a portion of the perineal strap.

In the drawings, the numeral 1 denotes 5 a belt which may be made of any desired material. Preferably, however, the belt is in the form of an elastic rubber strip. Reinforcing webs 2, made of canvas or the like, are folded on the ends of the belt 1 and extend longitudinally of the belt. The webs 2 ordinarily are cemented to the belt 1. One of the webs 2 carries eyes 3 held in place by rivets 3^a or otherwise, the rivets 3^a passing through both layers of the said 10 web 2 and through one end of the belt 1. Hooks 4 are mounted on the other reinforce-

ing web 2 and are held thereto by rivets 4^a which pass through both layers of the web and through the corresponding end of the belt 1. Ordinarily there is one pair of the hooks 4 and a plurality of pairs of the eyes 3, so that a circumferential adjustment of the belt 1 may be effected, the hooks 4 being engaged with the eyes 3, as will be understood readily from Fig. 2.

One end 5 of a perineal strap 6 is attached to the rear portion of the belt 1 by cementing or otherwise. The perineal strap 6 ordinarily is made of rubber. Intermediate its ends, the perineal strap 6 is 60 tapered, as shown at 21. The forward end of the perineal strap 6 terminates in a broadened head 7, the edges of which diverge as they extend upwardly, as indicated at 22. A reinforcing web 8 is folded, as 65 shown at 9 across the upper edge of the head 7, the web preferably being cemented to the head. The web 8 may be made of canvas. Hooks 10 are mounted on the web 8. The hooks 10 are held in place by rivets 10^a which pass through both walls of the web 8 and through the upper end of the head 7. A reinforcing web 12 which may be made of 70 canvas, is folded as shown at 14 across the belt 1 and is secured thereto by cementing 75 or otherwise. The web 12 carries eyes 11 held in place by rivets 11^a passing through both walls of the web and through the belt 1. Preferably there is a single pair of the hooks 10 on the web 8 of the perineal strap 80 6, whereas the eyes 11 on the web 12 of the belt 1 are duplicated both longitudinally of the belt and transversely thereof. It will 85 be observed that, owing to this construction, the upper forward end of the perineal strap 90 6 may be adjusted both longitudinally of the belt, and transversely of the belt, when the hooks 10 are engaged with the eyes 11.

A strip 15 which may be made of resilient rubber, or any other desired material, is disposed transversely of the head 7 of the perineal strap 6. The ends 16 of the strip 15 are folded across the upwardly diverging edges 22 of the head 7, so as to form a downwardly tapered pocket 18. The ends 16 of the strip 100 15 are overlapped on the head 7 and are secured thereto by cementing or otherwise. The meeting edges of the ends 16 are designated by the reference numeral 17. In the strip 15 at the sides thereof, slits 19 are 105 formed. The numeral 20 indicates a pad, adapted to be pushed downwardly into the 110

pocket 18, through the upper end thereof, and because the pocket is of downwardly tapered form, the pad will not work out through the lower end of the pocket. The 5 slits 19 open, as indicated in the drawings, to permit a transverse expansion of the strip 15, under the action of the pad 20. The pad 20 may be made of any desired material. A 10 resilient, hollow rubber ball will be found useful, but this detail is not insisted upon.

In practical operation, the ends of the belt 1 are connected, adjacent the side of the body of the wearer, by means of the hooks 4 and the eyes 3. The perineal strap 6 extends 15 downwardly along the hip of the wearer and the upper forward end of the perineal strap is connected with the belt by means of the hooks 10 and the eyes 11, as hereinbefore described, the pad 20 being held in this way, 20 in proper position on the rupture. Those skilled in the making of trusses will understand that the perineal strap 6 may be located so as to retain either a right hand rupture or a left hand rupture, and if there is 25 a double rupture, then two of the perineal straps 6 will be provided. These details lie well within the skill of a mechanic having the present disclosure before him, and a specific delineation thereof is considered unnecessary.

Having thus described the invention, what is claimed is:—

1. A truss comprising a belt; a reinforce-

ing web folded transversely upon the belt and secured thereto; a perineal strap having 35 one of its ends attached to the belt; a reinforcing web folded over the other end of the perineal strap; and separable fasteners carried by the webs, those fasteners which are carried by the web of the belt being duplicated both longitudinally of the belt and 40 transversely thereof, to permit an adjustment of the web-carrying end of the perineal strap both longitudinally of the belt and transversely of the belt.

2. A truss comprising a belt; a perineal strap attached at one end to the belt and terminating at its other end in a widened head having upwardly converging edges; means for detachably assembling the head with the belt; a strip disposed transversely of the head and folded across the diverging edges of the head to define a downwardly tapered pocket, the ends of the strip being overlapped upon and secured to the strap; the 55 strip being provided with slits located adjacent the diverging edges of the head; and a pad in the pocket.

In testimony that I claim the foregoing as my own, I have hereto affixed my signature in the presence of two witnesses.

HENRY DANIEL O'BRIEN.
